MEANS FOR ELIMINATING CORROSION IN
ECONOMIZERS

William E. Caldwell, New Rochelle, N. Y.

Application June 21, 1939, Serial No. 280,271

3 Claims. (Cl. 122—379)

This invention relates to steam generating plants of the type that are equipped with economizers and particularly to means for eliminating corrosion in the economizers.

In a modern high capacity steam generating plant an economizer is justified by economic considerations in most installations. However, the economizer has certain disadvantages from the standpoint of maintenance which at times are serious in their effect on the availability of the economizer and the boiler. The major cause of economizer maintenance is internal corrosion with consequent increase in flow resistance resulting from corrosion products and entailing reduced life for the economizer. In spite of highly efficient de-aerating apparatus provided in modern steam generating plants, some corrosion or oxidation takes place in the economizer. Many modern high pressure economizers are of completely welded construction which renders the internal cleaning of the tubes by the ordinary turbine cleaner impracticable. Therefore, it becomes necessary to provide such favorable water conditions for the economizer that internal corrosion may be eliminated in order to avoid such increase in flow resistance.

Alkaline feed water suppresses the usual corrosion tendencies due to oxygen or other causes. It is impractical to add sufficient alkalinity to the boiler feed water for producing appropriate alkalinity in the economizer since this would result in an excessive concentration in the boiler due to the evaporative process. Inasmuch as the normal feed water treatment for prevention of scale within the boiler results in fairly high alkalinity therein, a method heretofore employed to lessen corrosion in the economizer has been to discharge a small part, say 5%, of the blow-down water from the boiler to the suction side of the feedwater pump so that it mixes with incoming feed water and is delivered through the economizer. With some waters the addition of blow-down water at the feed pump suction causes the deposition of scale within the tubes of steam-heated bleed stage heaters. In other cases it is inconvenient to provide piping from the blow-down of the boiler to the pump suction. Another known method is to provide a small pump between the boiler blow-down connection and the inlet of the economizer to recirculate part of the blow-down water. The disadvantages of this system are that such a pump is rather expensive and complex for high pressures, it introduces added losses due to leakage past the high pressure packing and also requires additional power to operate the pump.

In accordance with the present invention the disadvantages of such prior arrangements are obviated by providing an eductor connected to the boiler at the blow-down or other suitable point and so arranged as to employ the ordinarily wasted energy in the feed water to draw alkaline water from the boiler and force it through the economizer and thence back into the boiler.

When certain chemicals such as phosphate are used for conditioning the feed water the boiler water must have a minimum alkalinity in order that the phosphate sludge resulting from the chemical reaction within the boiler with calcium and magnesium will not adhere to the boiler heating surface. Under such circumstances, it may not be practical to reintroduce a part of the boiler water to the economizer since the precipitated sludge or solids in suspension which are thereby carried into the economizer may adhere to the economizer surface. It is further not practical under the circumstances to maintain the water within the economizer at a sufficiently high alkalinity in order to prevent such an adherence, because maintaining such a high alkalinity within the economizer would in turn result in a too high concentration of alkali within the boiler proper. The use of organic compounds, such as tannin, to prevent the sludge formed within the boiler from adhering to the boiler heating surface, is open to the same objections. If alkali, tannin or similarly acting compounds are used in an economizer in the amounts necessary to prevent the adherence of sludge to its tube surface, an excessive amount of blow down from the boiler would be necessary to keep the boiler water concentration therein within suitable limits.

According to this invention under the above or similar conditions, I provide within the connection for reintroducing the boiler water of relatively high alkalinity into the economizer, means for removing substantially all of the precipitated sludge or solids in suspension from said boiler water thereby preventing its entering the economizer and either depositing in the economizer tubes or being carried over into the boiler and causing an accumulation of too high a concentration therein. I have further found that by the usual method of blowing down boilers now in use, the suspended solids do not blow off in proportion to the solids in solution. By the use of my means for removing the sludge the suspended solids are removed to a relatively greater extent than they would be by the usual blow down. Also if the normal blow down is 1½ to 2% and if I recirculate 4% of the water fed to the boiler thru the economizer, I will remove by

my means a greater amount of sludge or solids in suspension and will remove them in a concentrated form with a substantially smaller blow down.

How the foregoing, together with other objects and advantages as may hereinafter appear or are incident to my invention are realized, is illustrated in preferred form in the accompanying drawing, wherein—

Fig. 1 is a schematic view showing a steam generating plant having an eductor associated with the feed water system and arranged to draw water from the boiler through a sludge remover and cause it to be circulated through the economizer; and

Fig. 2 is a similar view showing part of the feed water system and illustrates a somewhat different manner of connecting the eductor.

In the drawing the numeral 10 designates a steam generating boiler equipped with an economizer 11 in which the feed water is heated before being discharged into the steam and water drum 12 of the boiler. Feed water treated to render it alkaline is withdrawn from a source of supply 13 by the feed water pump 14 and delivered through the feed water line 15 to the economizer. Interposed in the feed water line 15 between the pump 14 and economizer 11 are a shut-off valve 16 and a feed water regulating valve 17. The feed water regulating valve 17 is automatically controlled in any suitable manner, as in response to water level in the drum 12, so as to vary the amount of feed water delivered to the boiler through the economizer as the load upon the boiler, and hence the evaporating rate, rises and falls.

In the usual economizer the pressure drop at maximum flow is about 40 pounds and diminishes according to well-recognized laws as the flow decreases. In the conventional plant there is a substantial pressure difference across the feed water regulating valve 17 and in Fig. 1 there is shown a means of utilizing this pressure difference for drawing water out of the boiler and discharging it into the economizer at a higher pressure. An eductor 20 connected by piping 21, 22 to the boiler 10 is so arranged in a by-pass 23 formed by piping connected to the feed water lines at points beyond the inlet and outlet sides of valve 17 that part of the feed water flows through the by-pass around the valve and its energy is utilized to draw part of the water from the boiler and introduce it into the feed water line at a point beyond the valve 17. A suitable amount of boiler water recirculated through the economizer may be about four per cent, for example, of the feed water. In the connection between the boiler and the economizer there may be provided means for removing substantially all of the suspended solids or sludge from the boiler water before it is reintroduced into the economizer. Such means are shown diagrammatically at 27 in the pipe 22 and may be a filter, a deconcentrator or the like, and may be blown down through valved connection 28. The pipe connection 22 may be made to the boiler at any point considered suitable for removing concentrates and need not be connected directly to the boiler blow-down piping. The discharge pipe 28 from filter 27 may, however, be utilized as the only means for regularly blowing down the boiler. A discharge pipe 24 may also be provided and connected either to pipe 22 or directly to the boiler to dispose of blow-down water which it is desired to

remove from the boiler to reduce concentration therein.

Piping 25 between the feed water line 15 and pipe 21 connecting the eductor with the boiler forms a cooling connection for mixing relatively cooler feed water with the hotter boiler water so that cavitation and reduced eductor capacity may be avoided because the water from the boiler water approximates saturation temperature while the feed water is at times substantially below this.

Experience indicates that local corrosion is less prevalent where high water velocities prevail, as at high boiler ratings, and corrosion becomes 15 more active as the velocities diminish. The eductor 20 provides for this condition since at low ratings on the boiler the feed water regulating valve 17 approaches its closed position thereby increasing the pressure difference across the 20 valve and resulting in increasing the amount of water recirculated from the boiler through the economizer by the eductor 20. A valved by-pass 30 may be provided around filter 27. In shutting 25 down a boiler arranged as in Fig. 1, the valve 26 controlling the by-pass in which the eductor is located would be the last to be closed and this would result in increasing the pH value or alkalinity of the water in the economizer as the flow diminishes. At all ratings there will be substantial 30 recirculation of boiler water with consequent corrosion protection and a simultaneous removal of suspended solids from the recirculated water when the filter 27 is used.

The eductor shown in Fig. 2 functions in a 35 manner quite similar to that of Fig. 1, but is located directly in the feed line rather than in a by-pass around the feed water regulating valve. It may be seen that in this arrangement also the eductor utilizes the energy of the feed water to 40 draw water from the boiler and cause it to be delivered to the economizer.

Although an arrangement is shown in which alkaline feed water is admitted at the suction side of pump 14, this is merely illustrative and 45 not a prerequisite for successfully protecting an economizer by circulating through it alkaline water derived from the boiler. It is possible to introduce alkalinity to the drums of the boiler or other part thereof by a separate pump and thus 50 build up a concentration independent of alkalinity in the feed water itself.

Applicant's recirculation of boiler water to the 55 economizer through a filter within the recirculation line then performs the simultaneous functions of minimizing accumulation of sludge in the economizer while producing a proper alkalinity of the feed water to the economizer to prevent corrosion therein and in serving as a boiler blow down obviates the necessity for an otherwise excessive blow down from the boiler.

Applicant's filter 27 may be located in the line 15 beyond by-pass 23 and there serve to filter out the suspended solids carried over from the boiler and those formed in the feed water by a 65 possible reaction between the recirculated boiler water and feed water. With this arrangement the boiler may be blown down separately. Or a second filter may be installed in line 15, ahead at by-pass 23.

70 The present application is a continuation-in-part of my earlier application Serial No. 189,987, filed February 11, 1938.

What I claim is:

1. In a steam generating boiler arranged to 75 receive feed water from an economizer supplied

by a pump through a feed line having a flow regulating valve therein; a blow-down for said boiler; an eductor so connected to said blow-down and so associated with said feed water line as to utilize the energy of feed water to draw water from said boiler and introduce it into said feed line to flow through said economizer; and piping connecting said feed line at a point ahead of said eductor to the connection between the boiler blow down and said eductor for mixing feed water with water drawn from the boiler before it enters said eductor.

2. In a steam generating boiler arranged to receive feed water from an economizer supplied by a pump through a feed line having a flow regulating valve therein; a blow-down for said boiler; piping connected to said feed line beyond the inlet and outlet sides of said valve and forming a by-pass for feed water around said valve; and an eductor so connected to said blow-down and so located in said by-pass piping as to utilize the energy in the feed water flowing through said by-pass to draw water from the boiler and intro-

duce it into said feed line at the outlet side of said valve to flow through said economizer; and piping connecting said feed line at a point ahead of said eductor to the connection between the boiler blow down and said eductor for mixing feed water drawn from the boiler before it enters said eductor.

3. In a steam generating boiler arranged to receive feed water from an economizer supplied by a pump through a feed line having a flow regulating valve therein; a connection for the withdrawal of alkaline feed water from the boiler; piping connected to feed said line beyond the inlet and outlet sides of said valve and forming a by-pass for feed water around said valve; and an eductor so connected to said withdrawal connection and so located in said bypass piping as to utilize the energy in the feed water flowing through said bypass to draw water from the boiler and introduce it into said feed line at the outlet side of valve to flow through said economizer.
